UNITED STATES PATENT OFFICE.

GEORGE F. STONEY, OF LORAIN, OHIO, ASSIGNOR TO NATIONAL TUBE COMPANY, OF PITTSBURG, PENNSYLVANIA, A CORPORATION OF NEW JERSEY.

MOLD FOR TWYERS AND OTHER HOLLOW ARTICLES.

992,288.

Specification of Letters Patent. Patented May 16, 1911.

Application filed October 15, 1909. Serial No. 522,731.

To all whom it may concern:

Be it known that I, GEORGE F. STONEY, of Lorain, in the county of Lorain and State of Ohio, have invented a new and useful Mold 5 for Twyers and other Hollow Articles, of which the following is a full, clear, and exact description, reference being had to the accompanying drawings, forming part of this specification, in which—

10 Figure 1 is a sectional elevation illustrating the manner of forming the jacket core of the twyer mold; Fig. 2 is a side elevation partly in section showing the jacket mold removed from the forming box; Fig. 3 is a sectional elevation showing the way in which the center core is molded; Fig. 4 is a sectional elevation showing the completed twyer mold; Fig. 5 is a plan of the core ring with the detachable lifting handles in place thereon; Fig. 6 is a plan view of the chill drag plate.

15 My invention has relation to the molding of twyers and other hollow articles, and is designed to provide a mold of this character 25 which will not require the use of a drag section; and also to provide means of novel character for properly adjusting and centering the cores in the mold.

20 The precise nature of my invention will 30 be best understood by reference to the accompanying drawings, in which I have shown the preferred embodiment thereof, and which will now be described, it being premised, however, that various changes 35 may be made in the details of construction and arrangement of the several parts by those skilled in the art without departing from the spirit and scope of my invention.

Referring to Fig. 4, the numeral 2 designates the flask, 3 the jacket core set therein, 40 4 the center core, 5 the center core arbor, and 6 the chill drag plate upon which the flask 2 and the core jackets are set in a manner hereinafter described.

45 7 designates the sand filling of the mold.

In accordance with my invention, the center core 4 is molded in a core box 8, which is set on a master plate 9, in which is also set the vented core arbor 5. A hopper 9^a 50 is placed on the core box 8, and the box is rammed with green sand. To facilitate the handling of the core, the core arbor 5 carries

at its upper end a threaded sleeve 11, into which may be screwed a nut 12 having a handle 13. The jacket core 3 is formed in a core box 14, which is set on a stripping plate 15.

16 is the core mandrel, supported on the master plate 17.

18 is a core ring seated in the stripping plate 15, and having seats 18^a therein to receive tapered plugs 19 through which are threaded the lower ends of vent pipes 20, which extend upwardly into the space between the core box and the core mandrel. 65

19^a designates nuts which engage the lower threaded ends of the vent pipes.

21 is a hopper supported on the core box 14 and having a central cone 22 around which the sand is rammed down into the space around the vent pipes for the purpose of forming the core jacket. After this operation is completed, the jacket core is removed, by means of detachable handles 23, which engage the ring 18, and said ring with 75 the core thereon is supported on a plate 24 in the manner shown in Fig. 2 to permit the core ring to be removed.

In building up the twyer mold shown in Fig. 4, the center and jacket cores are placed 80 on the chill drag plate 6, the latter having a central recess 25 to receive the base portion 26 of the center core arbor 5. The drag plate 6 is also provided with openings 27 therethrough, countersunk at the upper face 85 of the plate to receive the plug 19, and also countersunk on the lower side to receive the nuts 19^a. The chill drag plate is provided with the groove 31, which communicates with the downwardly extending pouring 90 gate 32, and from which the hot metal flows upwardly into the mold. The lower portions of the vent pipes 20, between the lower end of the jacket core and the plugs 19, are provided with the sleeves or thimbles 33, which 95 form the openings into the large end of the hollow wall of the molded article.

The advantages of my invention arise from the provision of a mold which does not require the use of a drag section, and which is 100 provided with means whereby the center and jacket cores may be directly supported on a drag plate and properly centered and held thereon.

It will be obvious that various changes may be made in the details of the construction and arrangement of the parts without departing from the spirit and scope of my invention, since

What I claim is:

1. In a mold of the character described, a detachable center core arbor having a core supporting base, a drag plate having a seat 10 for said base and having seats to center a jacket core and means for securing the jacket core in centered position on said plate.
2. In a mold of the character described, a drag plate, a flask supported thereon, a center core having a core supporting base, said base detachably resting in a recess in said drag plate, anchoring means seated in the drag plate and a jacket core secured to the anchoring means.
3. In a mold of the character described a drag plate, a center core, an arbor for said core detachably supported directly on said drag plate, a jacket core having vent pipes therein, said pipes having projecting plugs

at their lower ends and the drag plate having seats for said plugs. 25

4. In a mold of the character described a drag plate having a central seat for a center core arbor and also having a series of concentric seats, a jacket core having centering means secured in said seats and a center core arbor having a core centering base detachably secured in place in the central seat for said arbor. 30

5. In a mold of the character described a jacket core having a plurality of vent pipes therein, said pipes having frusto-conical projecting portions at their lower ends, anchoring means on said projecting portions and a drag plate having frusto-conical seats for 40 the anchoring means.

In testimony whereof, I have hereunto set my hand.

GEORGE F. STONEY.
